UNITED STATES PATENT OFFICE.

CARL H. PETERSON, OF DENVER, COLORADO.

GARTER-SUPPORTER.

1,142,201.

Specification of Letters Patent. Patented June 8, 1915.

Application filed October 11, 1913. Serial No. 794,706.

To all whom it may concern:

Be it known that I, CARL H. PETERSON, a citizen of Sweden, residing at Denver, in the county of Denver and State of Colorado, 5 have invented certain new and useful Improvements in Garter-Supporters, of which the following is a specification, reference being had to the accompanying drawings.

This invention relates to garter supporters and more particularly to a device of this character which is designed for use as an attachment to men's under garments, the invention having for its principal object to produce a simple and efficient garter supporter which will permit of free and unrestricted movement and will not retard the blood circulation.

My invention has for a still further object to provide a device of the above character which is of great convenience and serviceability in actual use and will not add materially to the cost of the garment.

With the above and other objects in view, the invention consists in the novel features 25 of construction and the combination and arrangement of parts to be hereinafter more fully described, pointed out in the claims and shown in the accompanying drawings, in which—

Figure 1 is a view illustrating the preferred embodiment of my invention as applied in actual use. Fig. 2 is an enlarged perspective view of the device; Fig. 3 is a sectional perspective taken on the line 3—3 of Fig. 2; Fig. 4 is a detail fragmental perspective view showing a slightly modified form of the invention; Fig. 5 is a similar view illustrating still another modification.

Referring in detail to the drawings, 5 40 designates a band of linen or other suitable fabric which is provided with the longitudinal folds 6. These folds are securely stitched together adjacent one of their longitudinal edges, as indicated at 7. The band is adapted to be applied to the lower edge of the drawers leg, as clearly shown in Fig. 1, the latter being placed between the folds 6 of the band and securely stitched to said folds. By applying the device to the drawers leg 45 in this manner, a very permanent, efficient and secure attachment is produced which serves as a protection or reinforcement for the edge of the drawers leg. To one of the folds 6 of the band at the ends thereof, the

short sections of tape 8 are secured whereby 55 the ends of the band may be drawn tightly together and the tapes tied to retain the band in place.

At the lower edge of the band, where the same is folded upon itself, slits are cut at 60 spaced intervals, as indicated at 9, and through said slits the ends of the tabs 10 are inserted so that said tabs lie between the folds 6 of the band and are secured thereto by the rows of stitching 7. These tabs which 65 are of double thickness are provided with openings 11 to receive a stud 12 upon the attaching plate 13 of the garter straps 14. Each of the attaching devices for these garter straps which are provided at their upper 70 and lower ends, includes a loop member 15 for engagement over the head of the stud 12. The attaching devices upon the lower ends of said straps are adapted to be connected to the upper edge of the stocking in 75 the usual manner and thereby provide a support for the stocking upon opposite sides of the leg.

By providing the band 5 with the folds 6 and securing the tabs 10 between said folds 80 in the manner above explained, it will be obvious that said folds will protect the wearer's leg against irritation or chafing by the rubbing contact of the tab therewith which would be occasioned in the shifting movement of the hem or band. The band being secured about the wearer's leg by means of the tie strings 8, the tendency of the same to 85 shift is greatly minimized as the arrangement of the tabs dispenses with all projections upon the face of the band 5 with which the trousers might engage.

My improved garter support is particularly designed for use in connection with union under garments, the band 5, above described, taking the place of the hem on the lower edge of each leg. It will be obvious that the device may as well be used upon under garments of other construction. It will be understood that I do not desire to 90 be limited in this regard in putting the invention into practice.

In Fig. 4, of the drawings, I have illustrated a slightly modified means for connecting the garter straps to the band 5 wherein the tab 10 has one of its ends inserted into the slit 9 in the lower edge of the band, the free end being provided with a detachable

fastener indicated at 16, so that said free end may be extended through a loop 17 on the garter strap and the members of the fastener connected to detachably hold the strap in connection with the said tab.

5 In Fig. 5, I have shown still another modification wherein the tab 10' is disposed upon the exterior of the band at its lower edge and stitched thereto. This tab is provided with 10 an opening 11' in which a metal reinforcing plate 17 is arranged. The manner of connection of the garter strap to this form of the device is the same as that described in connection with the preferred form.

15 From the foregoing it is believed that the construction and manner of use of the several forms of my invention will be clearly and fully understood. My device provides 20 an efficient support for the stocking without occasioning the wearer any discomfort or restricting the free circulation of the blood. The application of my invention to the under garment does not add materially to the cost thereof and as there are no metal parts 25 upon the band 5 in the preferred form of the invention, the garment may be washed without removing the band therefrom. The invention as a whole is extremely simple in its construction and highly serviceable and 30 convenient in actual use.

While I have shown and described the preferred form and construction of the several parts, it is to be understood that the device is susceptible of still further modification, and I reserve the right to resort to all 35 such legitimate changes as may fairly fall

within the spirit and scope of the invention, as claimed.

What I claim is:—

1. In a device of the character described, 40 a leg encircling band having longitudinal folds extending the entire length thereof and stitched together adjacent to the line of folding of the band, said folds beyond the stitching being adapted to be arranged upon 45 opposite sides of the lower edge of a drawers leg and to be securely stitched thereto, said band at the line of folding thereof being provided at spaced points with slits, tabs having one of their ends disposed through 50 said slits and between the folds of the band and permanently secured to said folds, and tie strings secured at opposite ends of the band to one of the folds thereof.

2. In a device of the character described, 55 a leg encircling band having longitudinal folds stitched together adjacent to the line of folding, said folds beyond the stitching being adapted to be arranged upon opposite 60 sides of the lower edge of a drawer's leg and to be securely stitched thereto, tabs secured at one of their ends to the connected folds of the band and depending below the lower edge of said band, and tie strings secured 65 to opposite ends of said band.

In testimony whereof I hereunto affix my signature in the presence of two witnesses.

CARL H. PETERSON.
